[57] CLAIM

The ornamental design for a mobile telephone set, as shown and described.

DESCRIPTION

FIG. 1 is a front, left side and bottom perspective view of a mobile telephone set showing my new design in cradled relationship;

FIG. 2 is a front elevational view thereof,

FIG. 3 is a right side elevational view thereof,

FIG. 4 is a rear elevational view thereof,

FIG. 5 is a top plan view thereof,

FIG. 6 is a bottom plan view thereof,

FIG. 7 is a rear elevational view thereof showing handset separated from stand,

FIG. 8 is a front elevational view of a second embodiment thereof, the difference of the embodiment, vis-a-vis the first, being the frame of the display panel, and the shape of the skirt below the pushbuttons;

FIG. 9 is a front elevational view of a third embodiment thereof, the difference of this embodiment, vis-a-vis the first, being the upper speaker phone horizontal apertures substituted for the three round apertures in the first.
